UNITED STATES PATENT OFFICE.

WILLIAM W. McCORMICK, OF SANTA ROSA, CALIFORNIA.

THROAT-SHIELD.

SPECIFICATION forming part of Letters Patent No. 662,150, dated November 20, 1900.

Application filed March 15, 1900. Serial No. 8,716. (No model.)

To all whom it may concern:

Be it known that I, WILLIAM W. McCORMICK, a citizen of the United States, residing at 135 Third street, in the city of Santa Rosa, county of Sonoma, and State of California, have invented certain new and useful Improvements in Throat-Shields; and I do hereby declare the following to be a full, clear, and exact description of the said invention, such as will enable others skilled in the art to which it most nearly appertains to make, use, and practice the same.

This invention relates to improvements in surgical instruments, and more particularly to a shield for introduction into the thorax of a person being operated upon for any nasal trouble.

In the drawings, Figure 1 is an elevation of the invention as applied to the throat of a person. Fig. 2 is a rear view of the same. Fig. 3 is a cross-section of the same.

The invention has for its object to provide a shield which will prevent the introduction of hemorrhage or blood into the thorax or bronchi of the person being operated upon for any nasal ailment, while at the same time providing means for supplying air for breathing purposes, which is introduced from beyond the mouth; also, to provide means for carrying the blood off, so that the same is not precipitated into the mouth of the patient when being operated upon; and the invention consists in providing a shield constructed in the shape substantially shown in the drawings and of any suitable material--such as vulcanized rubber, aluminium, or similar material--which is stamped to provide a cavity C in the rear of the shield or on the side of the shield toward the thorax. The exterior of the shield A is such as will most readily accommodate itself to the posterior cavity of the mouth. From the cavity C is extended a flexible tube or pipe B, adapted to extend beyond the lips of the mouth. It is through the pipe or pipes B that air is drawn from the outside. The front of the shield A is shaped so as to form a valley or curved portion to direct the hemorrhage into the pipe D, which is extended beyond the outer edge of the mouth and which may be carried to a suitable receptacle for the hemorrhage.

In operations of the nature specified it has been proven in the past that the hemorrhage

has been exceedingly difficult to handle, as by reason of the position of the patient the blood has access to the thorax, in many cases causing what is termed "gagging" or exceeding discomfort both to the patient and to the operator.

The shield A shown in the accompanying drawings and herein described is in such shape that when placed in position the contractile action of the muscles at the rear of the mouth, together with the natural suction action of the lungs and organs connected therewith, will hold the same firmly in place. By providing the drainage-tube D all the blood is carried away from the thorax and the difficulties and inconveniences specified are avoided. At the same time by reason of the introduction to the rear of the shield A of the pipe B a sufficient supply of air is supplied to the lungs. With an appliance of this nature in position it is possible for the operator to work with greater convenience both to himself and to the patient.

Having thus described this invention, it is claimed—

1. In an instrument of the character specified, the combination with a suitable shield adapted to close the entrance to the thorax of the patient, of a tube opening upon the rear side of said shield and extending forwardly therefrom, whereby air is supplied to the patient through said tube and hemorrhage from the nose is kept from entering the thorax; substantially as described.

2. In an instrument of the character specified, the combination with a shield adapted to close the entrance to the thorax of the patient, of a drainage-pipe connected to the forward surface of the said shield and adapted to collect and deliver the hemorrhage beyond the mouth of the patient, and a suitable tube opening upon the rear side of the said shield and extending therefrom to a position forward and out of the path of the hemorrhage, said shield having a raised portion, or recess, in its rear surface to receive the said second-named tube; substantially as described.

In testimony whereof I have hereunto set my hand this 2d day of February, 1900.

WILLIAM W. McCORMICK.
